UNITED STATES PATENT OFFICE.

HENRY E. GERO, OF SOMERVILLE, MASSACHUSETTS.

ERASER-SHIELD.

SPECIFICATION forming part of Letters Patent No. 729,062, dated May 26, 1903.

Application filed February 12, 1903. Serial No. 143,080. (No model.)

To all whom it may concern:

Be it known that I, HENRY E. GERO, a citizen of the United States, residing at Somerville, in the county of Middlesex and State of Massachusetts, have invented certain new and useful Improvements in Eraser-Shields; and I hereby declare that the following is a full, clear, and exact description of the same, reference being had to the accompanying drawings, forming part of this specification.

The invention has reference to improvements in devices designed to shield or protect the main portion of written or printed matter immediately surrounding a letter or word during the erasing of such letter or word.

One object of the invention is to so construct an eraser-shield that it can be accurately positioned and held for the erasing of a letter or symbol located between two other letters or symbols.

Another object of the invention is to so construct a shield of this nature that it may be held firmly in position on a flat or curved surface.

Another object of the invention is to so construct a shield of this nature that the shield portion may be renewed from time to time.

Another object of the invention is to so construct a shield of this nature that it may be engaged, positioned, and held in place by a single digital.

The invention consists in such peculiar features of construction and combination of parts whereby the objects of the invention are carried into effect, as will in its preferred form be hereinafter more fully described, and pointed out in the claims.

Figure 1 represents a plan view of the improved eraser-shield positioned for the erasing of printed matter from a sheet of paper carried by a cylinder, as the roll of a type-writer. Fig. 2 represents a side elevation of the same, showing the manner of engaging and lifting the shield, preferably by the thumb of the left hand. Fig. 3 represents an end view of the shield shown as arranged for a curved surface and illustrating the gripping means on the under surface of the shield-carrier. Fig. 4 represents a side elevation of the shield proper in relation to a sectional view of the shield-carrier to indicate the extension of the

under surface of shield proper in line with the plane of the under surface of the carrier. Fig. 5 represents a plan view of the keeper for securing the shield to the carrier, the thumb-cap being omitted.

Similar numbers of reference designate corresponding parts throughout.

This eraser shield or guard comprises a shield proper formed of comparatively thin smooth material, such as celluloid, having openings of any desired size or shape through which access may be had to the letter, word, or symbol to be erased, while the adjacent letters are protected. This shield or guard is mounted on a carrier, by means of which it (the shield) is positioned and held from movement under the rubbing contact of the eraser.

As illustrated in the drawings, in its preferred form the carrier comprises the plate 6, having a cross-sectional configuration adapted to conform to the surface on which the shield is intended for use. The lower surface of this plate is roughened or provided with gripping portions, as shown at 7, Fig. 3, whereby this surface may be engaged with the surface of the paper therebeneath and when held against said paper may be securely positioned against accidental displacement. The edges of this plate 6 are turned inward to form the lips 8.

The keeper 9 has the members 10, adapted to be slightly crowded together and entered under the lips 8 of the plate 6. At its forward end this keeper has the depending lip 11, which extends down over the front edge of the plate 6, the edge of this lip conforming generally to the cross-sectional configuration of this plate. The upper surface of the keeper 9 is preferably furnished with the cap 12, adapted to receive the end portion of a finger or thumb, preferably the latter, whereby the shield may be lifted into position.

The shield proper is formed from a piece of thin flexible material of a transparent or semitransparent nature, such as celluloid. It has the carrier portion 13, located between the upper surface of the plate 6 and the under surface of the keeper 9, and the shield portion 14, extending in the plane of the under surface of the plate 6 and held in this posi-

tion by the lip 11 of the keeper, the shield portion 14 being furnished with openings of any desired shape or size.

In Fig. 5 I have shown a keeper 9' without the cap 12, as it is obvious that this construction might be preferred for some uses.

Reference to Fig. 3 will indicate the engagement of the gripping-surface 7 with the surface of the paper from which the erasure is to be made, whereby accidental displacement of the shield under the rubbing contact of the eraser is prevented, while reference to Figs. 1 and 2 will indicate the precision with which the shield may be adjusted to bring the opening—for instance, that through which the letter "F" appears—inmediately over the particular letter to be erased, this accurate adjustment being possible from the bearing of the shield portion 14 directly on the paper while held in position by the carrier.

I do not desire to limit myself to the exact construction herein shown and described, but only as herein claimed.

Having thus described my invention, I claim as new and desire to secure by Letters Patent—

1. In an eraser-shield a carrier, and a shield secured to the upper portion of the carrier and bent downward beyond the carrier to the plane of the lower surface of the carrier.

2. In an eraser-shield, a shield having portions extending in planes parallel to, but removed from each other, and a mounting for said shield.

3. In an eraser-shield, a carrier having a roughened contact-surface, and a shield extending from the carrier, to form a smooth continuation of said surface.

4. In an eraser-shield, a carrier comprising

a plate having securing members on its upper surface, a keeper adapted to engage such members, and a shield adapted to be removable secured to said carrier by the keeper.

5. In an eraser-shield, a carrier comprising a plate having inturned lips, a keeper working under said lips, and a shield having a portion located between the plate and the keeper.

6. In an eraser-shield, a carrier comprising a plate having a concaved roughened surface, and a shield secured to such carrier and having a portion forming an extension of such roughened surface.

7. In an eraser-shield, a carrier comprising a plate having a concaved roughened surface, a keeper having a lip extending over one end of said plate, and a shield having a portion located between the keeper and said plate and a bent portion between the lip of the keeper and the end of the plate.

8. In an eraser-shield, a carrier comprising a plate having a roughened surface and in-turned lips, a keeper fitting beneath said lips and having a thumb-cap, and a shield secured to said plate by said keeper.

9. In an eraser-shield, the combination with the plate 6, having the roughened surface 7 and the lips 8 8 and the keeper 9 having the members 10 10, engageable beneath said lips, and the lip 11, of the shield 14 having the portion 13 secured by the keeper, as and for the purpose described.

In testimony whereof I affix my signature in presence of two witnesses.

HENRY E. GERO.
